UNITED STATES PATENT OFFICE.

JOHN H. THOMPSON, OF ELYRIA, OHIO.

BRACKET.

1,096,967.

Specification of Letters Patent. Patented May 19, 1914.

Application filed December 12, 1913. Serial No. 806,164.

To all whom it may concern:

Be it known that I, JOHN H. THOMPSON, a citizen of the United States, residing at Elyria, in the county of Lorain and State of Ohio, have invented a certain new and useful Improvement in Brackets; and I do declare the following to be a full and complete specification, such as will be clear to those skilled in the art.

10 My invention relates to improvements in brackets and more particularly to wall brackets for supporting sinks lavatories and similar devices.

15 It is frequently necessary to suspend from a wall objects of this character, weighing as much as three hundred pounds and requiring three or four men to locate them.

20 One of the objects of my invention is to provide suitable means for quickly and securely attaching these objects to the wall or other support at the same time permitting them to be easily removed from the wall.

25 I also aim to provide means for locating the sink or other device with respect to a pipe or other object so that it may be quickly and accurately placed at the first effort without the gang of men having to mount and dismount the apparatus several times in a "cut and try" method as has been 30 the custom hitherto, a procedure which resulted in the loss of time, the useless expenditure of energy, the mutilation of much plaster, etc., inaccuracy in locating the apparatus and insecurity in its mounting.

35 Other objects of my invention and the invention itself will probably be best understood from an illustration of a particular embodiment of the same.

Referring now to the illustration:—Fig. 40 ure 1, is a plan view of an embodiment of my invention. Fig. 2, is a front elevation of the embodiment, Fig. 1. Fig. 3, is an end view of a section, through the line A—A of Fig. 2, showing the sink attached and 45 the water pipes in position. Fig. 4, is a sectional end view of the sink.

At 1, I show the base member, preferably long and flat. The base member is provided with means by which a sink or other object 50 is connected thereto; such means are here shown as a plurality of sockets 2, preferably on the upper edge and near the ends of the base. Just below the sockets, are screw holes 3, through which the base is attached to the 55 wall with screws or other suitable means. The base member is provided with long slots

4, which are so lengthened that a part of each is bound to fall over one of the studding in the wall, when screws or bolts are driven through these slots into the studding, 60 the bracket will be secured to the wall, the screws in the small holes 3, serving to prevent longitudinal movement of the bracket. The bracket is provided with a pendant member, here shown as located at the central part of the base member, extending 65 outward and downward at 9, and bent over at 20, substantially parallel with the base member. The part 20 is provided with guides for pipes or other objects, here shown 70 as holes 5.

When it is desired to support a sink or similar device from the wall, the pipes 21 having been already located, the ends 22 thereof sticking through the wall, the 75 bracket is so placed that the ends 22 of the pipes project through the openings 5, the workman sounds for the studding, drives the screws through the slots 4, into the studding and smaller screws through the openings 3, into the plaster to prevent sidewise movement of the bracket, then hangs the sink 8 upon the bracket, lugs 23 upon the sink engaging the slots 2, and the holes 7, in the sink being so located with respect to 85 the lugs 23 that they coincide with the ends of the pipes when the sink is in place.

I claim:—

1. In a device of the class described, the combination of a base member having a plurality of pockets in the upper side and near the ends thereof, said pockets adapted to cooperate with the lugs on an object whereby the bracket supports the same, said base member being provided with a plurality of 90 slots by which it may be connected to a wall and a pendant arm, integral with said base member, said arm being extended outward and downward from said base member, the end of the arm being bent downward, substantially parallel with the base member and provided with openings to engage pipes or other objects, substantially as described. 95

2. In a device of the class described, the combination of a base member provided 100 with means by which a sink is attached and supported thereby and provided with a plurality of slots in the upper part of said base member, means driven through said slots by which it is secured to a wall or other upright, a pendant arm extending outward and downward from the lower part of said base 110

member and integral therewith and circular openings in the lower part of said base member coinciding with similar openings in the sink.

3. In a device of the class described, the combination of a long flat base member provided with means by which a sink or other object may be attached and suspended therefrom and with longitudinal slots in the upper part of said base member a pendant arm integral with said base member, said arm extending downward and outward from said

base member, and terminating in an end piece substantially parallel with the base member and provided with openings in the lower part for engaging pipes or other objects, substantially as described.

In witness whereof, I have affixed my signature in the presence of two witnesses, this 9th day of Dec. 1913.

JOHN H. THOMPSON.
